RELIEF VALVE FOR PREVENTING THE
BURSTING OF LIQUID CONTAINERS

Vernon Merritt, Montgomery, Ala.

Application September 14, 1933, Serial No. 689,422

11 Claims. (Cl. 137—34.3)

My invention relates to a device in the nature of an automatic relief valve for preventing the bursting of liquid containers, such as pipes, fittings, radiators, water cooled engine blocks and the like, when subjected to freezing temperature.

In my Letters Patent No. 1,851,202, issued to me on March 29th, 1932, I have shown and described a relief valve of the plug type mounted in a suitable seat so as to penetrate into the container beyond the initial freezing zone and having its portion that is exposed within the container covered with a material adapted to prevent the establishment of a frost bond and preferably to insulate the valve so as to retard radiation of heat from the liquid in contact with it and thereby slow up the formation of ice about the inner end of the valve. The present invention contemplates certain improvements herein-after described in the construction and design of such valve.

One object is to improve the means for preventing the ice or frozen liquid as it forms in the container from adhering to, or forming a bond with, the valve so as to prevent it from operating freely. I have discovered that this object is best attained by forming the valve of a material of low heat conductivity such as bakelite or other suitable non-conducting substance which preferably has a highly polished exterior to reduce the adherence of the ice thereto.

My invention further contemplates that the valve, or its core whether of conducting or non-conducting material, may have applied over its highly polished or very smooth exterior a jacket or cover of soft resilient rubber having a very smooth or glazed surface which will expose to the liquid no irregular or rough surface to which the ice would adhere. It is contemplated that such a jacket shall be free to both contract or to creep on the valve as the ice forms about it so as to give and prevent the formation of an ice bond with it that will interfere with its free functioning.

Another object is to provide only a short taper seat for the valve, leaving its inner end to project beyond the seat and initial ice zone into the body of liquid in the container which will be brought under increasing pressure as the freezing of the liquid in the container progresses.

Another object is to latch the valve in seated position, the latch being releasable under abnormally high internal pressure to allow the valve to open fully and drain the container without having a repeated or periodic operation.

A further object is to provide a valve for the

purposes described having a positive means for retaining it in its closed position, such means however being releasable when subjected to abnormal pressures within the container so as to reduce or relieve the internal pressure.

A further object of my invention is to provide a spring-pressed valve of the character described with a releasable spring means which when subjected to abnormal internal pressures will act either to permit the valve to open freely and fully or will act to snap the valve open, the valve in either case remaining open until reseated manually.

My invention further contemplates the utilization of a spring-pressed latch to hold the valve to its seat until released in response to the valve's opening movement, the valve having a portion disposed in the path of the released latch and engaged thereby to snap the valve fully open.

My invention further contemplates providing a spring-pressed valve of the character described with a spring seat comprising separable members which become disengaged when the valve is forced open but which are adapted to be readily reengaged to reseat the valve in operating position.

A further important object is to so design the mounting for the yieldable or spring means, that holds the valve in working position as to avoid the possibility of ice forming from the escaping liquid so as to block the valve's opening movement.

A further object of my invention is to adapt the various yieldable valve mounting means shown to permit the valve to be opened freely manually, thus adapting it to serve as a drain cock.

My invention further comprises the novel details of construction and arrangements of parts, which in their preferred embodiments only are illustrated in the accompanying drawing which forms a part of this specification, and in which:

Fig. 1 is a top plan view of one embodiment of my invention having a spring latch retainer for a rubber coated valve.

Fig. 2 is a side elevation of the valve and its seat as shown in Fig. 1.

Fig. 3 is a vertical sectional view taken on the line III—III of Fig. 1.

Fig. 4 illustrates an embodiment of my invention wherein a bakelite valve is held seated by a spring having a releasable seat which is snapped loose when the valve is forced open.

Fig. 5 shows a plug valve of heat non-conducting material mounted in a motor block section by a releasable metallic disk forced into the hole

through which the valve projects into the liquid surrounding the motor cylinders.

Similar reference numerals refer to similar parts throughout the drawing.

5 In the embodiment of my invention illustrated in Figs. 1 to 3, I conventionally illustrate at 10 a wall of any liquid container such as a pipe, a vessel of any character, a radiator, a motor block, etc. A hole is bored and tapped therein 10 to receive the reduced threaded shank 11 of a valve seat member 12 which has an inwardly tapering bore 13 serving as a seat for my automatic relief valve.

The relief valve, as shown in these views, has 15 a body 14 which may be of metal or other conducting material but which is preferably of heat non-conducting material such as bakelite. This body is tapered to conform to the taper of its seat 13 and its exterior surface is made smooth 20 and highly polished. Over such exterior surface I apply a heat non-conducting sleeve or jacket 15 which is preferably very resilient rubber with its exterior surface finished so very smooth as to prevent or resist effectively the formation of a 25 frost bond therewith. The valve body has at its upper end outside of the valve seat an annular groove 16 to receive an internal shoulder formed in the rubber sleeve so as to lock the sleeve in position. The upper end of the valve 30 is provided with spaced lugs 17 to receive between them the end 18 of an S-shaped lever and to hold the pivot pin 19 which connects the valve to this lever. The valve seat 12 has out-turned marginal bearing arms 20 between which the 35 lever is pivotally mounted by a pin 21 with its free end bent up to form a handle 22.

A spring 23 is formed of bent wire arranged 40 to provide spaced parallel sides each having a coil or helix therein and each connected at its lower end to the base of the adjacent bearing arm 20 and at its upper end to a cross arm or latch 24 which is adapted to be engaged and retained between the upper ends of the bearing arms as a keeper 25 and the upwardly curving 45 edge 26 of the lever so as to exert a pressure on the lever to hold it to its seat and provide a lock or detent which will latch the valve set in its closed position against jolts or accidental displacement.

50 The valve projects substantially beyond its seat and its smooth inner end penetrates into the liquid in the container beyond the zone of initial freezing thereof so as to be exposed to the increasing pressure on the unfrozen liquid as the 55 freezing action progresses.

The valve is so mounted that there is no possibility of liquid escaping past it becoming trapped or held so as to freeze and block the valve's opening movement.

60 Having thus latched the valve in its seated position, as the internal pressure rises due to freezing, the unfrozen liquid exerts an increasing force acting on the inner end of the tapered valve to unseat it. When a pressure sufficient 65 to unseat the valve exists, the valve moves outwardly forcing the spring latch arm 24 over its keeper 25 whereupon the spring will snap against the valve lever and force the valve to swing outwardly clear of its seat and permit the free outflow of liquid sufficient to protect the container 70 against bursting. The spring will hold the valve open but it can be readily reset by forcing the valve to its seat and again engaging the latch arm 24 with its keeper 25 as shown in Fig. 2.

75 At any time the lever end 22 can be pressed

down manually to trip the latch and open the valve to drain the container or relieve its internal pressure.

In Fig. 4 I show a simpler valve construction 5 as applied to a pipe or container 27. Here the 10 valve 28 is of the plug type formed of bakelite or like heat non-conductor with a highly polished exterior surface and has a top flange 29 and a center boss 30. The seat 31 for the valve is formed in the container wall, and both valve 10 and seat are preferably tapered. The container has an annular flange 32 rising therefrom concentric with and spaced from the seat 31 so that a gasket 33 may be placed under the valve flange 29. A cap 34 of spring metal slit to provide 15 resilient arms 35 will snap over the flange 32 and releasably interlock therewith. The wide base coil of a spiral spring 36 is seated in a bead in the top of the cap and its inner end surrounds the boss 30 on the valve. The spring is 20 preferably interlocked with both the cap and boss to hold the valve and cap assembled. The top of the boss is spaced from the cap and the spring engagement between the cap and flange 32 is sufficiently strong to exert a pressure through 25 spring 36 on the valve that will hold it to its seat against any but abnormally high internal pressures.

In operation, the valve assembly is readily 30 mounted by pressing the valve to its seat until the cap is engaged with flange 32. When freezing occurs and the internal pressure on the unfrozen liquid rises, the valve will be forced outwardly and in so moving its boss will engage the cap 34 and force it loose, whereupon the liquid 35 will freely escape from the container.

In Fig. 5 I show a further modification of my 40 invention. Here an opening 37 is formed in the wall of a motor block 38 and a metallic mounting disk 39 is forced into such opening until it 45 seats firmly but releasably therein. The disk carries a plug valve 40, of non-heat-conducting material or comprising such material, which is disposed to project substantially into the liquid in the motor block to a point well beyond the 50 zone of initial freezing indicated by the dotted line 41. Preferably, this plug will prevent access of the internal liquid to the disk. The opening 37 may be reduced at its inner end to form a 55 tapered seat 42 for the valve 40. The internal pressure will rise as the freezing progresses until it is high enough to exert a force on the plug that will unseat the disk and expel the valve to permit the unfrozen liquid to escape before the container bursts.

In the embodiments of my invention hereinbefore described, no provision is made for what 60 may be termed the periodic opening and closing of the valve to progressively relieve internal pressure as the freezing proceeds as that action may be accomplished by the utilization of the valves shown with the type of spring mounting described by my Letters Patent aforesaid.

Without further description, it is thought that 65 the features and advantages of the invention will be readily apparent, and it will of course be understood that changes in the form, proportion and minor details of construction may be resorted to, without departing from the spirit of the invention or its scope as claimed.

70 What I claim is:—

1. In combination, a liquid container, and a 75 freeze plug mounted in the wall of said container and having a highly polished exterior surface of a material resistant to the establishment there-

with of a frost bond, which surface is adapted to project into the liquid within the container beyond the zone of initial freezing thereof, and retaining means coating with the container and plug to hold the latter seated against normal internal pressures and adapted to permit the expulsion of the plug from its seat to freely drain said container.

5. 2. In a means to prevent liquid containers from bursting under freezing strains, a freeze plug adapted to be mounted in the wall of a container and having its inner end which is adapted to project into the liquid within the container highly polished, and a rubber sleeve covering said 10 polished portion and itself provided with a polished exterior surface where exposed to the liquid.

3. In combination, a liquid container and a poor-heat-conducting freeze plug mounted in a wall of said container and adapted to project a 20 substantial distance thereinto, whereby pressures developed by the process of freezing will displace said plug, and spring means normally holding said plug in said wall and capable of withdrawing it when once unseated.

25. 4. In a device of the class described, a conical valve responsive to the pressure exerted by a freezing liquid, a valve seat member having a conical valve seat, said conical valve adapted to engage said seat, a fulcrum carried by said seat member, a lever pivotally mounted on said fulcrum and connected to said valve, and spring means acting upon said lever to normally hold said valve in seated engagement with said valve seat and when released to fully withdraw the 35 valve from its seat.

5. In a device of the class described, a valve responsive to the pressure exerted by a freezing liquid, a valve seat member having an exteriorly threaded boss and a valve seat, a fulcrum carried by said member, a lever pivotally mounted on said fulcrum, said valve connected to one end of said lever, said valve being of a sufficient length to extend a substantial distance beyond its seat into the vessel, and spring means for normally 40 retaining said valve in engagement with its seat.

45. 6. In a device of the class described, a conical valve responsive to the pressure exerted by a freezing liquid, a valve seat member having an exteriorly threaded boss and conical valve seat, a fulcrum carried by said seat member, a lever pivotally mounted on said fulcrum, said valve connected to one end of said lever, said valve being of a sufficient length to be adapted to extend a substantial distance beyond its seat into the 50

freezing liquid, spring means for normally retaining said valve in seated engagement with said valve seat, and a handle portion on said lever to provide for the manual release of said valve.

7. A valve responsive to the pressure exerted by a freezing liquid comprising a valve seat, a valve operatively associated therewith, said valve being of a poor-heat-conducting material and having a covering of smooth rubber of high elasticity, and retaining means for holding said valve 10 in seated engagement with said valve seat against normal internal pressures.

8. In a device of the class described, a valve responsive to the pressure created by a freezing liquid, a valve seat member, a lever connected 15 to said valve and having a bight portion, a fulcrum carrying member integrally formed with said valve seat member and rockably supporting said lever, said fulcrum carrying member having a portion projecting above said bight portion, and a spring mounted upon said seat member and having a latch portion engageable between said bight portion and said fulcrum carrying member projecting portion for normally holding said valve 20 in seated engagement with said valve seat.

25. 9. A valve responsive to the pressure exerted by a freezing liquid comprising a valve seat, a valve operatively associated therewith and having a tapered inner end adapted to be exposed to said liquid, comprising an exterior polished surface of 30 a poor-heat-conducting material and having a covering for said surface of smooth rubber of high elasticity, and retaining means for holding said valve in seated engagement with said valve seat against normal internal pressures.

35. 10. In combination with the relief port of a liquid container, a freeze protection plug inserted in said port, the plug having an elongated rigid tapering core adapted when the valve is seated to project into the container beyond the zone of 40 initial freezing, the plug having its surface polished and a soft polished rubber sleeve fitted over the polished plug and interposed between it and the walls of the relief port and the liquid in the container.

45. 11. The combination with a liquid container having a relief port, of a tapered expellable freeze plug composed of poor-heat-conducting material with a highly polished exterior surface seated in said port and adapted to project beyond same 50 into the liquid in the container, and means to hold said plug against expulsion by normal internal pressures within said container.

VERNON MERRITT.
